UNITED STATES PATENT OFFICE.

PAUL BURMEISTER, OF NEAR FULDA, MINNESOTA, ASSIGNOR OF ONE-HALF TO CHARLES WEST AND ONE-HALF TO DELMER M. MEAD, OF FULDA, MINNESOTA.

DOOR-OPERATING MECHANISM.

Application filed June 23, 1923. Serial No. 647,389.

To all whom it may concern:

Be it known that I, PAUL BURMEISTER, a citizen of the United States, residing near Fulda, in the county of Nobles and State of Minnesota, have invented new and useful Improvements in Door-Operating Mechanism, of which the following is a specification.

This invention relates to doors for garages, warehouses and the like, and has for its object the provision of a door construction, mounting and operating means of such a nature that upon the actuation of a treadle at either side of the door, by passage of a vehicle thereover, will cause the door to be automatically opened or closed as the case may be without it being necessary for the driver to alight.

An important and more specific object is the provision of a door construction and mechanism of this character in which the door is slidably mounted and moved to open or closed position by a motor having a reversing switch operated by movement of the treadles located in the roadway.

Another object is the provision of a mechanism of this character in which the motor will be automatically cut off when the door reaches its entirely open or entirely closed position.

Another object is the provision of a device of this character which is equipped with a control lever whereby the motor means may be set in operation manually at the door, and which is equipped with other control means operable from a remote point such as from the office, or the like.

An additional object is the provision of a mechanism of this character which will be comparatively simple and inexpensive in manufacture and installation, highly efficient in use, durable in service, a great time and labor saver and a general improvement in the art.

With the above and other objects and advantages in view the invention consists in the details of construction to be hereinafter more fully described and claimed and illustrated in the accompanying drawings, in which:

Figure 1 is a sectional view through one wall and the floor of a building looking toward the inside of a slidably mounted door and showing my operating means associated therewith,

Figure 2 is a horizontal section through a portion of the building showing a plan view of the door operating mechanism, this view being taken on the line 2-2 of Figure 1,

Figure 3 is a detail section on the line 3-3 of Figure 1,

Figure 4 is a detail section on the line 4-4 of Figure 3,

Figure 5 is an enlarged detail plan view of a portion of the operating mechanism showing the connection of the treadle operating shaft with the motor control bar,

Figure 6 is a similar view of a slight modification,

Figure 7 is a fragmentary elevation looking toward the door and showing the position of the parts when the door is at one limit of its movement,

Figure 8 is a similar view showing the position of the parts when the door is at the other limit of its movement,

Figure 9 is a detail elevation of the reversing switch,

Figure 10 is a section therethrough on the line 10-10 of Figure 9,

Figure 11 is a detail elevation of the base of the switch,

Figure 12 is a diagram of the electric circuit.

Referring more particularly to the drawings the letter A represents the door-way of a garage or other building and B represents the door which is shown as provided with hangers C carrying wheels D rolling upon a track E. In carrying out the present invention I provide a sprocket 15 journaled at one side of and above the door opening, its mounting being within or upon a suitable bracket. At the other side of and above the door opening I provide a shaft 16 mounted in suitable bearing brackets and carrying a sprocket 17 about which is trained a chain 18 which has its upper stretch trained about idlers 19 suitably mounted on the wall of the building. The lower stretch of the chain is secured to the upper portion of the door as indicated at 20. The shaft 16 also carries a pulley 21 about which is trained a belt 22 engaging about a pulley 23 mounted on a shaft carrying a gear 24 meshing with a pinion 25 on the shaft of an electric motor 26 of the reversible type.

Mounted upon the wall near the door is a control switch for the motor, which

switch is indicated broadly by the numeral 27. This switch consists of a rotatable casing 28 of insulating material mounted on a base 29 and movable in a groove 30 therein (Figures 9 to 12). This casing is hollow and in the wall thereof are embedded contacts 31 carried by stems 32. Two of these stems are connected by wires 33 and 36 with the terminals of the field winding of 10 the motor and the other two are connected by wires 34 and 35 with the armature winding as indicated in the diagram. Located within the casing or shell is a stationary disk 37 of insulating material carrying metallic arms 38 and 39 which have their ends extending to the periphery of the disk and terminating in contact shoes. These members 38 and 39 have connected therewith the line wires 40 and 41 of the current in the 20 building.

The motor is illustrated as being of the series wound type and it is well known that in such a motor to effect reversal thereof, it is merely necessary to reverse the direction of the current flow through either the field coil or the armature. In the action of this switch it will be seen that when the case or shell 28 is turned so that the arm 38 touches the contacts with which the wires 33 and 34 are connected, the arm 39 touching the contacts with which the wires 35 and 36 are connected, current will flow from the source, through the wire 40, arm 38, wire 33, field winding of the motor, through 25 the wire 36, through the arm 39 and wire 41 back to the source. At the same time current flows from the source through the wire 40, arm 38, wire 34, armature coils, wire 35, arm 39 and wire 41 back to the 30 source. The motor will then be operated in one direction. When the shell 28 is turned so that the arm 38 engages the contacts to which the wires 33 and 35 are connected, and the arms 39 engages the contacts to which the wires 34 and 36 are 35 connected, current will flow from the source, through the wire 40, arm 38, wire 35, through the field, wire 36, arm 39, and wire 41 back to the source. At the same time current will flow from the source through the wire 40, arm 38, wire 35, through the armature wire 34, arm 39 and wire 41 back to the source. In this second instance the current flow through the field is in the same 40 direction as in the first instance, but the flow through the armature is reversed so that the direction of rotation of the armature will be reversed.

The operating means consists of shafts 43 journaled in the road-way or drive way at both sides of the door and extending into gear housings 44 which may be buried or embedded in the earth or concrete, depending upon the construction of the approaches 45 to the doorway. Within these housings the

shafts 43 carry bevel gears 45 which mesh with other bevel gears 46 on the ends of shafts 47 which extend transversely of the drive way and which carry treadles 48 adapted to be engaged by the wheels of 70 vehicles. The inner ends of the shafts 43 are encircled by coil springs 49 secured at one end to the shafts as shown at 50 and having their other ends 51 engaging the arms 52 of a forked lever 53 pivoted on the 75 shafts 43.

Arranged at one side of the door-way is a vertically extending longitudinally slideable rod 54 which has its lower end pivotally connected at 55 with the lever 53 and which has its intermediate portion carrying or formed with stops 56 located above and below a longitudinally shiftable spring pressed pawl plate 57 having an opening 58 through which the rod or bar 54 is slid- 85 able. This plate is slideable on brackets 59 fixed to the wall and is guided in its movement by pins 60 passing through slots 61 in the plate. The spring for urging the plate in one direction is indicated by the numeral 90 62. Between the stops 56 and the bar 54 is formed with three notches 63, 64 and 65 selectively engagable by a tooth 66 at one edge of the opening 58 (Figure 4).

At its upper end the bar 54 terminates 95 in a slotted head 67 (Figure 7) within the slot of which is engaged a pin 68 carried by one arm of an angle lever 69 pivoted on the door frame and including a second up-standing arm 70 somewhat overlying the 100 chain 18. Pivotal connected with the angle lever is a link 71 which is connected with an operating arm 72 on the switch casing 28. Mounted on the chain at suitably spaced points thereon are stops 73 and 105 74 adapted to engage the angle lever 69 when the door reaches its fully open or closed position and for the purpose of returning the switch to its neutral position.

For effecting manual control I provide 110 an elongated lever 75 which is pivoted within a suitable bracket 76 mounted on the wall and which is pivotally connected at 77 with the rod 54.

For effecting control from a remote point 115 I provide a cable 78 trained over suitable pulleys 79 and 80 and having its ends connected with opposite sides of the angle lever arm 70. This cable should extend to the office of the building or any other desired headquarters so that the mechanism may be operated irrespective of the treadles and manual control lever.

In the operation it will be seen that if the door is shut and a vehicle drives over 125 the treadle 48 on the approach side the shaft 47 of the depressed treadle will operate to turn the associated shaft 43 by virtue of the intermeshing gears. Whenever the shaft 43 130 is thus turned, it is quite apparent that the

- lever 53 will be moved downwardly whereupon the bar 54 will be moved downwardly until the uppermost stop 56 engages the pawl plate 57. The springs 49 operate to prevent undue movement in any respect so that injury to the mechanism will be prevented. It should be stated that when the door is closed the motor is idle and the reversing switch is in its neutral or circuit breaking position, the tooth 66 on the pawl plate being engaged within the notch 64. When the bar 54 is moved downwardly, as above described, it results in rocking the angle lever 69 whereupon the link 71 turns the switch casing 28 and brings two of the contacts thereof in engagement with the arms 38 and 39 of the stationary disk. Current then flows through the motor and the rotation of the motor is imparted through the gearing and belting to the shaft 16 so that the sprocket 17 thereon will be driven. The result will be that the driving of the chain 18 will move the door to its open position. When the door is thus opened, the stop 73 will engage against the angle lever arm 70 and effect rocking thereof which will lift the bar 54 to its normal or neutral position and at the same time turn the switch casing 28 to its circuit breaking position.
- When the vehicle has passed through the door-way and drives over the other treads 48 the shafts 43 will be rotated in the same manner but in the opposite direction and the bar 54 will be moved upwardly for throwing the switch in its other position so that current will be supplied to the armature of the motor in a reverse direction. The motor is thus reversed and the sprocket 17 driven so that the chain will operate to return the door to normal or closed position. When the door reaches its closed position the stop 74 will engage the angle lever arm 70 and return the switch to its cut off position.
- It is obvious that the bar 54 may be shifted in one direction or the other by means of the hand lever 75 and it is equally true that the same result may be obtained by pulling properly upon the cable 78.
- In order that locking may be effected it is preferable to provide a hook 81 on the door frame engageable with a pin 82 or the like on the hand lever and when this is done it is quite obvious that the bar 54 can not be moved until the hook is disengaged. At such a time it is apparent that depression of a treadle will have no effect whatever on the mechanism inasmuch as the springs 49 will simply yield with the bar 54 remaining inactive.
- In some instances it is not necessary to have a treadle at each side of the door and in Figure 6 I have disclosed this modification in which the construction and operation are entirely the same except that I provide only one shaft 43 which has the same type

of spring connection 49 with the forked lever 53 which connects with the bar 54.

From the foregoing description and a study of the drawings it will be apparent that I have thus provided a simply constructed and consequently inexpensive door operating mechanism which will be entirely automatic or which may be manually controlled if preferred. The device is bound to be a great time and labor saver especially when used in connection with garages where the doors must be closed and opened often. Owing to the simplicity of the construction and the fewness of the parts it is apparent that there is little to get out of order so that the device should have a long life and satisfactorily perform all of its functions.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I claim:

1. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, and treadle operated means at both sides of the door-way for moving said rod.

2. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means at both sides of the door-way for moving said rod, and a yieldable connection between the treadle operating means and the rod to permit the latter to remain stationary and the former to move inactively.

3. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means at both sides of the door-way for moving said rod, and a pivoted lever operatively connected with said rod whereby to effect movement thereof and control of the motor manually.

4. Operating mechanism for a slidably mounted door, comprising a chain trained about sprockets and connected with the

door, a motor having a drive connection with one sprocket, a reversing switch for the motor, a longitudinally movable rod located at one side of the door-way and connected at one side of the door-way and connected with the switch, and treadle operated means at both sides of the door-way for moving said rod, an angle lever pivotally mounted and having one arm connected with said rod, and stops carried by the chain and engageable with said angle lever for moving the switch to neutral position when the door reaches either limit of its movement.

5. Means for operating a slidably mounted door consisting of sprockets mounted above the door opening, a chain trained about said sprockets and connected with the door, a motor having a drive connection with one sprocket, a reversing switch for the motor consisting of a rotatable shell member of insulating material having a central circular opening, contacts extending within the opening and connected with the terminals of the field and armature windings of the motor, a stationary disk mounted within the opening and carrying contact members connected with a source of current and adapted to be brought into engagement with selected pairs of said first named contacts, a movably mounted rod connected with the rotatable shell of said reversing switch, shafts journaled at opposite sides of the door-way and having a yieldable connection with an intermediate shaft connected with said rod and treadles on said shafts.

6. Operating mechanism for a slidably mounted door comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, means for locking said rod against movement, and a yieldable operating connection between the treadle and the

rod for permitting movement of the former while the latter remains inactive.

7. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position. 60

8. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position. 65

70

9. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position, said means including a pawl plate spring 75

pressed into engagement with an edge of the rod, and the rod being formed with notches engaged by said plate.

80

10. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position, said means including a pawl plate spring 85

pressed into engagement with an edge of the rod, the rod being formed with notches engaged by said plate, and stops on the rod above and below the pawl plate for limiting 90

movement of the rod.

In testimony whereof I affix my signature.
PAUL BURMEISTER.

4
door, a motor having a drive connection with one sprocket, a reversing switch for the motor, a longitudinally movable rod located at one side of the door-way and connected with the switch, and treadle operated means at both sides of the door-way for moving said rod, an angle lever pivotally mounted and having one arm connected with said rod, and stops carried by the chain and engageable with said angle lever for moving the switch to neutral position when the door reaches either limit of its movement.

5. Means for operating a slidably mounted door consisting of sprockets mounted above the door opening, a chain trained about said sprockets and connected with the door, a motor having a drive connection with one sprocket, a reversing switch for the motor 15 consisting of a rotatable shell member of insulating material having a central circular opening, contacts extending within the opening and connected with the terminals of the field and armature windings of the 20 motor, a stationary disk mounted within the opening and carrying contact members connected with a source of current and adapted to be brought into engagement with selected pairs of said first named contacts, 25 a movably mounted rod connected with the rotatable shell of said reversing switch, shafts journaled at opposite sides of the door-way and having a yieldable connection with an intermediate shaft connected 30 with said rod and treadles on said shafts.

6. Operating mechanism for a slidably mounted door comprising a chain trained about sprockets and connected with the door, a motor having a drive connection 40 with one sprocket, a reversing switch for the motor, a longitudinally movable rod located at one side of the door-way and connected with the switch, treadle operated means in advance of the door-way for moving said rod, means for locking said rod 45 against movement, and a yieldable operating connection between the treadle and the

rod for permitting movement of the former while the latter remains inactive.

7. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position. 50 55

8. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position. 55 60 65

70 said means including a pawl plate spring pressed into engagement with an edge of the rod, and the rod being formed with notches engaged by said plate. 75

9. Operating mechanism for a slidably mounted door, comprising a chain trained about sprockets and connected with the door, a motor having a drive connection with one sprocket, a reversing switch for the motor, a longitudinally movable rod located at one side of the door-way and connected with the switch, treadle operated means in advance of the door-way for moving said rod, and means for temporarily holding said rod in either selected position, 80 85

90 said means including a pawl plate spring pressed into engagement with an edge of the rod, the rod being formed with notches engaged by said plate, and stops on the rod above and below the pawl plate for limiting movement of the rod.

In testimony whereof I affix my signature.
PAUL BURMEISTER.

Certificate of Correction.

It is hereby certified that Letters Patent No. 1,532,171, granted April 7, 1925, upon the application of Paul Burmeister, of near Fulda, Minnesota, for an improvement in "Door-Operating Mechanism," were erroneously issued "one-half to Charles West and one-half to Delmer M. Mead," as assignees, whereas said Letters Patent should have been issued to the inventor, said Burmeister, and Charles West and Delmer M. Mead, said West and Mead being assignees of one-half interest only in said invention, as shown by the records of assignments in this Office; and that the said Letters Patent should be read with this correction therein that the same may conform to the record of the case in the Patent Office.

Signed and sealed this 2d day of June, A. D. 1925.
